UNITED STATES PATENT OFFICE.

ANTHONY VANDERVELD, OF GRAND RAPIDS, MICHIGAN.

BRISTLE-BED FOR BRUSH-MACHINES.

1,070,861.

Specification of Letters Patent.

Patented Aug. 19, 1913.

Application filed January 13, 1913. Serial No. 741,835.

To all whom it may concern:

Be it known that, I, ANTHONY VANDERVELD, a citizen of the United States, and resident of Grand Rapids, in the county of Kent and State of Michigan, have invented an Improved Bristle-Bed for Brush-Machines, of which the following, taken in connection with the accompanying drawings, is a specification.

10 In brush machines in which tufts of bristles are set in brush blanks, it is necessary that a supply of bristles be had and that they be fed to the machine as required.

It is with the bristle supplying means that this invention is concerned, and it has for its purposes and objects to make a reservoir, storage compartment, or as it is known in the art, a bristle bed of new and improved structure, which will hold a large supply of bristles, feed them to the machine in a new and advantageous manner, which will allow the insertion of an additional supply of bristles by an easy and efficient method, which will allow the removal of any loose bristles in the bed quickly and readily, and which when the supply in the bed is nearly exhausted, will give notice of the fact by an automatic disconnection of certain parts of the device, rendering the feeding of the bristles thereafter practically ineffectual. All of these desirable features are incorporated together with many others, in the structure illustrated in the drawings as one embodiment of my invention, and in which,

Figure 1 is a side view of the upper portion of a brush machine, showing the position and relation of the bristle bed with respect to the other parts of the machine, the bed having one of the plates at the ends of the bristles removed to better show the structure of the bed. Fig. 2 is a sectional view through the bed, the mounting of the bed on the frame of the machine also being shown. Fig. 3 is a plan view of the bed. Figs. 4 and 5 are side and plan views, respectively, of the follower member positioned back of the loose bristles and forcing them forward toward the bed opening. Fig. 6 is a side view of the bed similar to the view of the bed shown in Fig. 1, with the parts in different position, and indicating certain operations of the bed as will be later described. Figs. 7 and 8 are plan and side views, respectively, of the bristle

bundle receiving member, located back of the follower.

The brush machine is of the type shown in my copending application, Serial No. 741,834; filed, Jan. 13, 1913, and it has cams 60 2 and 3, operating through arms 4 and 5 to work the staple guide and inserter portions of the machine, said operations occurring as described in said application. Feed wheel 6 having slot 7 is provided and 65 is mounted so as to come at the open end of the bristle bed 8, which is the subject matter of this invention. All of these cams, arms, etc., are mounted on the frame 9 of the machine, and the bristle bed is also 70 mounted on an upright 10 of the frame, being spaced some distance therefrom by the journal lug 11 as shown in Fig. 2. The bed comprises relatively stationary parts, the base 12, side 13, and top 14 partially 75 covering the space above the base. Base 12 and top 14 are curved in outline and the side 13 is curved to correspond fitting between the base and top and rigidly connecting them through the bolts 15, leaving an 80 open side between them. In the open space so provided adjustable plates 16 are positioned and are adjustable toward and from each other by reason of the slots 17 formed in top 14, through which thumb screws 18 85 are inserted and screwed into plates 16 thereby fixing them with respect to the top. This adjustment of the plates 16 is provided to allow for different lengths of bristles, which are to lie lengthwise between 90 plates 16.

The feed wheel 6 is positioned at the front of the bristle bed and immediately adjacent to the front open end thereof. Said wheel, as described in my co-pending application, has rotary movement backward through practically half a circumference, then forward to initial position, the slot therein being in this manner, presented at the opening in the bristle bed and receiving bristles which on its return the wheel carries to the staple guide and delivers thereto. In order that the bristles shall be always in shape to enter the slot I have provided a follower member 18' which lying back of the bristles is made use of to force the bristles forward and in contact with the wheel whereby whenever the slot 7 is presented to the bristles, they will be forced therein. This follower member com- 100 105 110

prises in structure a body 19 and two extensions 20 integral therewith, making in appearance a fork as shown in Fig. 5. A handle 21 is riveted securely to the body of the follower, and is of use in operating the follower lengthwise of its support as will be hereafter described. The ends of the extensions 20 are made pointed so as to easily pass through the loose bristles.

10 The body portion of the follower 18' is mounted in a support 22 lying in a slot therein and secured by plates 23 which lie across the slot at either end thereof and are fastened by screws 24 to the support, binding the follower in the slot and securely holding it. At any time it is desired to move the follower with reference to the support, the screws may be loosened and the follower moved lengthwise of the support by 15 means of the handle 21. The support 22 is pivotally mounted between its ends on a bolt 25 which is threaded into a lug inserted in the downward side extension 26 of the base 12. Connected with the support 22 and 20 movable therewith is a grooved roller 27 having a notch 28 cut therein and shaped to receive the roller 29 mounted on the end of the member 30, which normally seats in the groove of roller 27, and which has attached thereto at its other end a weight cord 25 leading through an opening in the upwardly projecting lever 32 to and over a pulley 33, a weight (not shown) being attached to the free end of the cord. Follower 30 30 18' being mounted in its support 22 extends through the base 12, the forked extensions 20 of the follower passing through slots 34 in the base. The normal tendency of the weight cord is to rotate the roller 27 in a 35 clockwise direction, carrying the follower support 22 with it, and forcing the follower forward thereby pressing any bristles in front of the follower against the feed wheel. The location of the notch 28 in roller 27 is 40 such, however, that when the follower comes in proximity to the feed wheel, that is when there are few bristles in front of the follower, the roller 29 and its supporting member 30 will disengage from notch 28 and the 45 groove in roller 27, thereby taking away the force which normally operates the follower forward, and rendering the feed of the bristles into the slot of the feed wheel practically inoperative. Parts 30 being free will 50 be drawn back until it contacts with lever 32 by which it is stopped. A handle 35 extending laterally from member 30 is used to return the roller to notch 28 and the part 30 to the groove in roller 27. The slots 34 55 in base 12 extend nearly to either end of the base and allow the follower extensions 20 to operate through a wide arc.

Projecting upwardly from the base 12, at either side of the slots 34, and downwardly 60 from the top 14 substantially opposite to

these on the base, are ribs 36 which serve to keep the bristles from bearing against the whole inner surfaces of base 12 and top plate 14, thereby reducing friction and facilitating the movement of the bristles toward the feed wheel. Toward the front of the bristle bed, the lower ribs are discontinued and between their ends there is mounted on a pivot 37, the plate 38, its pivotal mounting allowing it to swing toward the top 14. Mounted on the same pivot 37 and passing under plate 38 is a lever 39 which extends beyond plate 38 and is bent upwardly, carrying at its free end a small roller 40, which lies against a cam 41 secured to and movable with the feed wheel 6. The cam is so shaped that on the backward movement of the feed wheel, it elevates the roller 40 and the lever attached thereto, thereby carrying plate 38 toward the top 14 and further compressing the bristles positioned therebetween so that when the slot 7 is presented to the bristles they will be under considerable pressure and will the more freely enter. On the return of the feed wheel, this pressure will be relieved, allowing the follower to force the bristles forward.

The operation of the device so far as described will now be readily apparent. Starting with the bed full or nearly full of loose bristles in front of the follower fork extensions 20, substantially as shown in Fig. 1, the tension of cord 31 imparted to roller 29 serves to force the follower against the bristles thereby pushing them forward to the open end of the bed against the feed wheel. On the backward throw of the feed wheel, the plate 38 is elevated and the bristles next to the feed wheel are compressed to a still greater extent so that when the slot 7 comes into position to receive bristles, they are under their greatest pressure and readily enter the slot under the influence thereof. This operation may be 95 repeated until the supply of bristles in the bed gets low, at which time the notch 28 in roller 27 has gone far enough that the tangential force exerted on the roller 27 against the shoulder of the notch serves to draw the 100 roller 29 from the notch, the shoulder of the notch having become so positioned that it will allow this, freeing the follower from the force that impels it forward, and allowing it to be easily returned to original position, the member 30 and roller 29 being 105 replaced as described heretofore.

Bristles in their loose state are not easy to handle and cause considerable trouble if it is necessary to so handle them. I have provided means whereby the bristles need to be manually handled only in bundles, avoiding the trouble and annoyance stated. To this end, the top 14 does not extend over the whole of the bed but only about half way as 110

shown, leaving an open trough back of the top in which the bundles of bristles, as they are received, may be easily laid. Bristles are made up, commercially, into bundles about two to two and one half inches in diameter, and are held by a cord passing around the bundle. To receive and hold the bristle bundles, I have provided the retaining device 42, illustrated in Figs. 7 and 8, and consisting of a solid body 43 having attached at either side thereof near one end, the curved prongs or forks 44, said prongs extending in the same direction as the body 43 for a distance then 15 being bent at an angle thereto and curved substantially in the arc of a circle. At its other end the body 43 is formed into a journal by means of which the device is pivotally attached to the follower support 20, having a loose connection therewith so as to be easily movable with respect thereto. The prongs or fork members 44 extend through the slots 34 in the base 12, and the curved portions thereof come to about the 25 outer edge of the spacing plates 16. In normal position, this holding or retaining device rests on the bottom of the slots 34 and is in position to receive the bundles of bristles. This position is indicated by 30 dotted lines in Fig. 6 and in full lines in Fig. 1. After the bundles of bristles have been dropped in and are resting on member 42, the cord that is passed around them is cut placing them in a loose state above the retaining member. When the supply of bristles in front of the follower gets low, the member 42 may be turned into the position indicated in full lines in Fig. 6, and the 35 bristles carried on said member will be carried upward and over against the back of the follower. By loosening the screws 24, the follower may be carried along the slot in the follower support 22 until the fork extensions 20 thereof are below the bottom 40 ribs 36 upon which the support 22 and follower may be turned backward to such position that when the follower is returned to normal place in its support, it will lie back of the bristles. This is indicated in the 45 dotted line position of the follower in Fig. 6. The parts 44 are spaced far enough apart that the extensions 20 will pass between them. In this manner a new supply of bristles may be placed in the bed without 50 the inconvenience and annoyance of handling them in a loose state.

This structure is also of utility in taking out any bristles which may be in a loose state in front of the follower. If for any 55 reason the bristles in the bed are not wanted and they are to be removed, the screws 24 are loosened and the follower drawn back along the slot in the follower support 22 until it is clear of the bristles and then the 60 follower support is turned forward until

the follower is in place to be inserted in the bristles at the extreme forward portion of the bristle bed. The follower is then pushed into its normal place in the follower support, the pointed ends of parts 20 allowing this, when the loose bristles will be back of the follower. Upon turning the follower backwardly the loose bristles will be carried with it and will fall on the retaining member. A cord, indicated by numeral 45 may then be passed back of the bristles through a slot 46 cut in the base 12 for that purpose, and the loose bristles bound into a bundle after which it may be lifted from the bed and other bristles inserted. When these operations are gone through with, the roller 29 and part 30 may be disconnected from the rest of the device, handle 35 readily permitting such manipulation, and they can be returned after the device is in shape to feed bristles to the machine.

I have fully described a complete and operative structure as an embodiment of my invention. Such specific disclosure, however, is to be taken as merely diagrammatic and illustrative of the invention, and not in any sense as limiting, the scope of the invention being limited only as stated in the appended claims.

Having now fully described my invention, what I claim as new and desire to secure by Letters Patent is:—

1. A bristle bed for brush machines comprising a curved base member, a curved top member, and a pivotally mounted follower member operating between the base and top to force bristles placed between the base and top out of the bristle bed.

2. A bristle bed for brush machines comprising a compartment having an open end for receiving bristles, a follower for forcing bristles out of the open end of the compartment, means to press the follower against the bristles, said means becoming inoperative when the follower reaches a predetermined position in the bed.

3. A bristle bed for brush machines comprising a compartment for receiving bristles, an outlet for said compartment, a follower for exerting pressure on the bristles placed in the compartment, a feed wheel located adjacent the outlet, and means operated by the feed wheel to periodically exert an increased pressure on the bristles nearest the outlet of the compartment.

4. A bristle bed for brush machines comprising a bristle receiving compartment, a follower for exerting pressure on loose bristles placed in the compartment, and separate means positioned in the compartment to receive and hold bristles either loosely or in bundles back of the follower.

5. A bristle bed for brush machines comprising a trough like receptacle for carrying bristles, a cover for a portion of the trough

forming an inclosure therefor, means operating under the cover to force bristles placed under the cover out of the receptacle and means positioned in the receptacle back of the cover to receive and hold bristles either loosely or in bundles.

6. In a bristle bed for brush machines, a compartment for receiving bristles, a follower in said compartment for exerting pressure on the bristles in front thereof, and means whereby the follower may be removed from the compartment and reinserted at any desired position therein through loose bristles.

15 7. In a bristle bed for brush machines, a bristle receiving compartment having a slotted base member, a follower pivotally mounted beneath, and extending through the slotted base member, and means to operate said follower in one direction.

20 8. In a bristle bed for brush machines, a bristle receiving compartment having an open end and means to periodically restrict the size of the opening at said end comprising a member mounted at one side of the opening and operable toward the opposite side.

30 9. In a bristle bed for brush machines, a closed compartment having open ends to receive and discharge bristles, and an open sided trough adjacent to the compartment into which bundles of bristles may be inserted.

35 10. In a bristle bed for brush machines, a bristle receiving compartment, a follower pivotally mounted without said compartment, extending therein and operable lengthwise thereof.

40 11. In a bristle bed for brush machines, a curved and slotted base member, a receptacle for receiving bristles formed above the base member, a bristle follower movable through the slotted base member and a bristle receiving member also operable therethrough.

45 12. In a bristle bed for brush machines, a receptacle for receiving bristles, a follower mounted to traverse the receptacle, pivotal mounting provided for the follower, and a bristle bundle receiving device mounted on the same pivot with the follower.

50 13. A bristle receiving compartment comprising a fixed base, a fixed top, adjustable sides, and open ends, and a plate pivotally mounted adjacent one of the open ends and adapted to move to partially close said end.

55 14. In a bristle bed for brush machines, a

base slotted member, adjustable side members, a follower mounted to traverse the base member, a bristle receiving member mounted to traverse the base member and means whereby said follower and bristle receiving member may be made to traverse the base member independently.

15 16. In a bristle bed for brush machines, a receptacle for receiving bristles, a pivotally mounted follower, a support therefor, means operatively connected to the support whereby the follower is forced in one direction, said means automatically disconnecting from and thereby becoming inoperative to influence the follower upon the attainment of a predetermined position by the follower.

20 17. In a bristle bed for brush machines, a receptacle for receiving bristles, a follower pivotally mounted and operable about its pivot to traverse the receptacle, a bristle receiving member mounted on the same pivot as the follower and independently operable to traverse the receptacle, and means whereby the follower may be withdrawn from the receptacle thereby permitting the bristles carried by the bristle receiving member to be placed in delivery position in the receptacle.

25 18. In a bristle bed for brush machines, a receptacle for receiving bristles, a delivery end to said receptacle, a wheel having a slot to receive bristles from the receptacle, mounted adjacent to the delivery end, a cam attached to the wheel, a plate pivotally attached to a wall of the receptacle in proximity to the delivery end thereof, and a lever under the plate and operable by the cam to carry the plate toward the opposite wall of the receptacle.

30 19. In a bristle bed, a follower, a support therefor, a roller attached to the support and pivotally mounted, a notch cut in the roller, a roller received in the notch and having attachment to a supporting member therefor, a cord attached to said member and placed under stress thereby serving to operate the roller first mentioned about its pivot and actuate the follower.

35 20. In testimony whereof I have hereunto affixed my signature in the presence of two witnesses.

ANTHONY VANDERVELD.
